Primary Examiner — Sheryl Lane*Assistant Examiner* — Mark T. Philippss(74) *Attorney, Agent, or Firm* — Neal, Gerber & Eisenberg LLP(57) **CLAIM**

The ornamental design for an inflator, as shown.

DESCRIPTION

FIG. 1 is a perspective view of an inflator of our new design.

FIG. 2 is a right-side elevational view of the inflator.

FIG. 3 is a front elevational view of the inflator.

FIG. 4 is a left-side elevational view of the inflator.

FIG. 5 is a rear elevational view of the inflator.

FIG. 6 is a top plan view of the inflator; and,

FIG. 7 is a bottom plan view of the inflator.

The broken lines represent portions of the Inflator and form no part of the claimed design.
